(57) **CLAIM**

The ornamental design for a tray for articles, as shown and described.

DESCRIPTION

FIG. 1 is a perspective view of a first exemplary embodiment of a tray for articles showing my new design, shown in a folded configuration.

FIG. 2 is a left elevation view of the tray for articles of FIG. 1, the right elevation view is a mirror image.

FIG. 3 is a front elevation view of the tray for articles of FIG. 1, the rear elevation view is a mirror image.

FIG. 4 is a top plan view of the tray for articles of FIG. 1. FIG. 5 is a bottom plan view of the tray for articles of FIG. 1.

FIG. 6 is a plan view of the tray for articles of FIG. 1 shown in an unfolded configuration.

FIG. 7 is a perspective view of a second exemplary embodiment of a tray for articles, shown in a folded configuration.

FIG. 8 is a left elevation view of the tray for articles of FIG. 7, the right elevation view is a mirror image.

FIG. 9 is a front elevation view of the tray for articles of FIG. 7, the rear elevation view is a mirror image.

FIG. 10 is a top plan view of the tray for articles of FIG. 7. FIG. 11 is a bottom plan view of the tray for articles of FIG. 7; and,

FIG. 12 is a plan view of the tray for articles of FIG. 7 shown in an unfolded configuration.

The broken lines shown illustrate parts of the article that form no part of the claimed design.

1 Claim, 12 Drawing Sheets
